UNITED STATES PATENT OFFICE.

JOSEPH T. BAILEY, OF PHILADELPHIA, PENNSYLVANIA.

DESIGN FOR A BADGE.

SPECIFICATION forming part of Design No. 33,493, dated November 6, 1900.

Application filed October 9, 1900. Serial No. 32,553. Term of patent 14 years.

To all whom it may concern:

Be it known that I, JOSEPH T. BAILEY, a citizen of the United States, residing in the city and county of Philadelphia, State of Pennsylvania, have invented and produced a new and original Design for Badges, of which the following is a specification, reference being had to the accompanying drawings, forming part thereof.

10 The leading feature of my design for a badge is the representation of the head of a horse and a wreath surrounding the same.

Figure 1 represents a face view of a badge embodying my design. Fig. 2 represents a 15 section thereof on line x x , Fig. 1.

In the drawings, A designates the badge,

having on the face thereof the representation of the head of a horse B and a field C, which said head occupies.

D designates the representation of a wreath 20 composed of a series of leaves E and berries F, the same surrounding said field.

Having thus described my invention, what I claim as new, and desire to secure by Letters Patent, is—

25 The design for a badge substantially as shown and described.

JOSEPH T. BAILEY.
